APPARATUS FOR TESTING LIGHT DISCRIMINATION

Maarten A. Bouman, Utrecht, Netherlands, assignor to The Nederlandse Organisatie voor Toegepast-Natuurwetenschappelijk Onderzoek Ten Behoeve van de Rijksverdediging (The National Defence Research Council T.N.O.), The Hague, Netherlands, a corporation of the Netherlands

Application March 31, 1955, Serial No. 498,394

Claims priority, application Netherlands April 3, 1954

3 Claims. (Cl. 88—20)

My invention relates to an apparatus for examining the discriminating capacity of human beings between light of different intensity and of different colour.

The main object of my invention is a novel and simple apparatus by means of which several stimuli can be compared simultaneously.

The apparatus consists essentially of two compartments separated by a thin partition wall. The walls of the compartments are covered with a diffusely reflecting white paint as used in photometer spheres—for example zinc-oxide—and provided with openings through which light of adjustable intensity and adjustable colour can be admitted. In the partition wall holes are provided which are so small and close to each other that from some distance they cannot be seen separately.

These openings are arranged in recognizable, for instance geometrical configurations, which may be rectangles or other simple geometrical configurations.

A part of the wall of one of the compartments is left open, so that a window or opening is formed through which the partition wall can be seen.

The partition wall contains a number of geometrical configurations constituted by perforations which hereafter will be referred to as test areas. The arrangement of the holes is preferably identical for the individual configurations but the size of the holes in the individual configurations is different. A person placed at some distance before the apparatus sees the light reflected by the partition wall and the light passing through the openings, which comes from the compartment behind the partition wall. If the illumination in the back compartment is the same as in the front compartment the configurations cannot be seen by the observer. If the luminous intensities of the walls of both compartments are slightly different some of the configurations can be seen and the number of configurations which can be seen is a measure of the capacity of the observer to discriminate between light of different intensity.

The same applies when the back and front compartments are illuminated by light of the same intensity but of different spectro-composition; i.e. of different color.

My invention is further illustrated by a drawing wherein two embodiments of my new apparatus are shown.

Fig. 1 is a general view of a first embodiment of the apparatus.

Fig. 2 is a top view, partly in section of the apparatus.

Fig. 3 is a general view of a second embodiment.

Fig. 4 is a detail of the embodiment illustrated in Fig. 3.

In Fig. 1, 1 is a box, 2 is a slidable partition which can be adjusted. In this partition a number of rectangles 3, 4, 5, 6, 7 are shown, provided with holes which in every individual rectangle are of the same size but of different sizes in the several rectangles. In the side walls a number of openings are made which can be obscured partially or wholly by adjustable lids 11.

2

These openings are provided at both sides of the partition 2. An incandescent lamp 9 is situated in front of the openings 8 so that the light emerging from this lamp is distributed over both compartments.

5 In the opposite wall similar openings are made. The walls of both compartments are covered with white diffusely reflecting paint. In order to compensate for the loss of brightness in the front compartment due to the window 12 a corresponding portion of the walls of the back compartment may be blackened.

10 In the openings through which the light emerging from the incandescent lamp is admitted into the compartments a milk glass plate is provided in order to promote the uniform distribution of the light.

15 An observer placed before the apparatus will see the partition wall 2 through the opening 12. This opening is preferably large enough to see a number of the configurations simultaneously. When the illumination in both compartments is very different the observer can clearly see all test areas from which light rays emerge through the window 12 in the direction of his eyes.

20 When, however, the difference in the intensity of the illumination is made smaller, e.g. by adjusting the slides 11, the number of test areas which can be distinguished from the surrounding part of the partition wall becomes less and less. The number of test areas which can be seen at a predetermined slight difference of brightness in the compartments gives a reliable indication of the discriminating capacity of the observer with respect to 30 intensity differences.

25 Exactly the same procedure applies if the capacity for discriminating between colours is to be examined. The colour of the light in the back compartment can be made different from that in the front compartment by means of filters. The intensity can be adjusted to the same value in both compartments by adjusting the slides 11.

35 It may be remarked that the opening 12 must be located at some distance from the wall 2 and that the general illumination in the room where the examination takes place should not be too high.

40 If a portion of the walls of the back compartment is blackened for the reasons stated above this blackened part should not be visible through the holes in the partition wall.

45 Preferably the small openings in the partition wall are made so that the width thereof at the backside of the partition wall is larger than at the frontside. Under these circumstances the walls of these holes are not visible.

50 The configurations constituted by the arrangement of the holes in the partition wall need not be squares or other simple geometric configurations but can be letters or ciphers, subjected however to the condition that they are equally recognizable.

55 It can be shown that if in a colour triangle C_1 is the colour of the illumination of the partition, C_2 that of the wall behind the partition, the resulting colour of the test area which is delimited by the geometric configuration, is on the line C_1C_2 in the triangle. The point of the line C_1C_2 corresponding with the colour of the test area depends in a well known manner on the colour and the intensities of the illumination of the wall in the back compartment and the frontside of the partition.

60 65 If the intensity of colour C_1 is B_1 , that of colour C_2 is B_2 , and the fraction of the test area covered by the holes is α , then the resulting brightness B of T is

$$B = (1-\alpha)B_1 + \alpha B_2$$

70 75 If $B_1 = B_2 = B$, then the colour C of the test area is found by the equation $CC_1:CC_2 = \alpha:(1-\alpha)$

Hence when observed from a sufficient distance, the

sensation corresponding to C_1 , B_1 can be compared with that of C , B .

The diameter of the holes in the partition wall may vary from about 0.1 to about 1 mm. and the centers of the holes may be 1.5 mm. apart from each other.

The actual dimensions of an apparatus that has been used with very satisfactory results were as follows:

The area of the partition wall comprising the test areas was 10 x 15 centimetres, the test areas themselves measuring 1 x 5 cm. The test areas are separated by non-perforated strips of the partition wall. The opening 12 is of such size that when observed from a distance of about 5 metres the light from six test areas reaches the eyes of the observer.

For technical reasons α can hardly be made larger than $\frac{1}{2}$. The value $\alpha=1$ can be added by cutting out the whole test area. When the test area must cover a larger part of the line C_1C_2 than for the region of ω -values:

$$\begin{aligned} 0 < \alpha < \frac{1}{2} \\ \alpha = 1 \end{aligned}$$

a fraction of the test area may be blackened. If for instance the fraction of the test area corresponding to the holes is α a fraction β may be blackened. Then if B_1 is the brightness of the surroundings of the test area and B_2 the brightness of the walls of the back compartment, the brightness B of the test area will be

$$(1-\alpha-\beta)B_1 + \alpha B_2 = B$$

The colour C on the line C_1C_2 is defined by the equation

$$\alpha B_2 : (1-\alpha-\beta)B_1 = (CC_1) : (CC_2)$$

The condition for equal brightness of the test area and its surroundings is $B_1=B$, or $\alpha B_2=(\alpha+\beta)B_1$, and thus

$$(\alpha+\beta)B_1 : \alpha B_2 = (CC_2) : (CC_1)$$

So by providing test areas having different α 's and β 's any colour between C_1 and C_2 can be compared with C_1 .

Obviously the blackened parts of the frontside of the test area must consist of uniformly distributed small black areas.

If desired the surroundings of the test area could be blackened partially by uniformly distributed small black areas. When γ is the blackened fraction of this part of the plate B_1 in the formulae is to be replaced by γB_1 .

The apparatus illustrated in Fig. 3 is of the same general type as that of Fig. 1. The shape of the compartments in this case, however, is nearly spherical in order to improve the uniformity of the illumination (brightness). As in Fig. 1 there are a front compartment indicated by 30, and a back compartment 31.

Between the spheres a flat partition wall 32 is arranged which is provided with a number of test areas 33 of the same type as already have been described in connection with Fig. 1.

The partition wall 32 is slidably mounted in suitable guides 34, 35. The part 36 of the back compartment opposite the partition wall is flattened. The opening 37 in the front compartment, the part of the partition wall between the spheres 30 and 31 and the flattened part 36 have the same size and shape. Thus the shapes of both spherical compartments are identical. To compensate for the loss of brightness in the front compartment 30, due to the view opening 37, the backside of the partition wall is blackened.

In each of the compartments the light of four incandescent lamps is introduced by means of optical systems having their focus at 38 and 39 respectively. Preferably this focus should be located as nearly opposite as possible to the test areas and the flattened part 36 respectively in order to obtain the greatest possible brightness combined with a uniform illumination of said parts of the compartments.

The incandescent lamps of which only two are shown in each of the compartments are indicated at 40, 41 and 42, 43.

They are mounted in little boxes 44, 45, each provided with a partition 46, 47 respectively, having four openings 48, 49 respectively.

Opposite each of the lamps an optical system is located consisting of a condenser lens 50, a filter 51 and a polaroid 52. Instead of a polaroid an adjustable diaphragm or a neutral wedge may be used. As an alternative the currents in the lamps may be adjustable. All optical systems are of the same type and a description of the remaining systems is therefore superfluous.

The optical systems are mounted in tubular members 53 which are welded on the outer surface of the compartments.

The boxes 44 and 45 wherein the lamps are mounted are provided with holes at 54, 55 and 56, 57 respectively.

Bars 58 and 59 extend through the holes 54, 55 and 56, 57 and carry the boxes 44 and 45.

In the box 45 a rotatable member 60 is mounted. This member has the shape shown in Fig. 4.

In this figure the small circles indicated by the reference numbers 61, 62, 63 and 64 indicate the positions of the four incandescent lamps in the box 45.

In front of the apparatus a third compartment is provided. This compartment is illuminated by a number of incandescent lamps 66, 65 and the inner surfaces are painted white, whereas the surfaces 68 and 69 are blackened for obvious reasons.

The brightness of the inner surfaces of the third compartment is adjusted so as to be equal to the brightness of the spheres 30 and 31.

In order to test the equality of the brightness of the spheres 30 and 31, a test area of the partition is used for which $\alpha=1$. If the surroundings of this test area cannot be seen against the background constituted by the flattened portion 36 the brightness in both spheres is the same.

To obtain colours of the same brightness the member 60 is used. The procedure is as follows:

Circle 61 represents the lamp producing white light and the other circles represent the lamps producing coloured light. The white lamp and one of the coloured lamps are turned on and then the member 60 is rotated. The intensities of the lamps are adjusted until the flickering is reduced to a minimum. Then the brightnesses of the white illumination and the coloured illumination are the same. Obviously the equality of the brightness thus obtained has a subjective character and as a rule will be different for different human beings.

I claim:

1. An apparatus for testing light discrimination comprising two adjacent compartments, a partition dividing said compartments, said partition having groups of a plurality of small perforations arranged in recognizable configurations, the perforations comprising each group being of equal diameter and the perforations being of different diameters for each group, a viewing opening in one of said compartments opposite said partition, said partition being directly viewable from said viewing opening, means for illuminating each of said compartments, and means for adjusting said illumination whereby different light characteristics may be established in each compartment.

2. An apparatus as claimed in claim 1, wherein the diameter of the perforations is greater on one side of said partition than on the other, whereby the walls of said perforations are not visible when viewed from said viewing opening.

3. An apparatus as claimed in claim 1 wherein said illuminating means is a different color for each compartment.
